US0D1040491S

(12) **United States Design Patent** (10) Patent No.: **US D1,040,491 S**
(45) Date of Patent: ** Sep. 3, 2024

(54) **SHOE**

(71) Applicant: **PUMA SE**, Herzogenaurach (DE)

(72) Inventor: **Brendon M. Dowling**, North Weymouth, MA (US)

(73) Assignee: **PUMA SE**, Herzogenaurach (DE)

(**) Term: **15 Years**

(21) Appl. No.: **29/821,196**

(22) Filed: **Dec. 28, 2021**

Related U.S. Application Data

(63) Continuation of application No. 29/732,739, filed on Apr. 27, 2020, now Pat. No. Des. 944,504.

(51) **LOC (14) Cl.** 02-04

CLAIM

The ornamental design for a shoe, as shown and described.

DESCRIPTION

FIG. 1 is a top, left, front perspective view of an ornamental design for a shoe;

FIG. 2 is a front elevational view of the shoe of FIG. 1; FIG. 3 is a rear elevational view of the shoe of FIG. 1; FIG. 4 is a left side elevational view of the shoe of FIG. 1; FIG. 5 is a right side elevational view of the shoe of FIG. 1; FIG. 6 is a top plan view of the shoe of FIG. 1; and, FIG. 7 is a bottom plan view of the shoe of FIG. 1.

The broken lines are included for the purpose of illustrating portions of the shoe that form no part of the claimed design.

1 Claim, 7 Drawing Sheets
